UNITED STATES PATENT OFFICE

2,284,786

ACCOUNTING MACHINE

Paul H. Williams, Dayton, Ohio, assignor to The National Cash Register Company, Dayton, Ohio, a corporation of Maryland

Original application June 4, 1938, Serial No. 211,817. Divided and this application July 19, 1939, Serial No. 284,249

4 Claims. (Cl. 235—60)

This invention relates to improvements in combined adding machines and typewriters, commonly referred to as accounting or bookkeeping machines, and is particularly directed to improvements in consecutive numbering mechanisms. This application is a division of application Serial No. 211,817, filed June 4, 1938.

The object of the invention is the provision of novel means for controlling and operating a consecutive number device.

With this and incidental objects in view, the invention includes certain novel features of construction and combinations of parts, the essential elements of which are set forth in appended claims and a preferred form or embodiment of which is hereinafter described with reference to the drawings which accompany and form a part of this specification.

In the drawings:

Fig. 1 is a longitudinal sectional view, taken just to the right of one of the amount banks, showing said amount bank and its associated actuator mechanism, for positioning the type carrier and the totalizer wheels associated with said amount bank.

Fig. 2 is a side elevation, as observed from the right of the machine, illustrating the machine operating mechanism and the controlling mechanism associated therewith.

Fig. 3 is a right side elevation of the mechanism for controlling and operating the consecutive number device.

Fig. 4 is a sectional view showing, in detail, one denominational unit of the consecutive number device.

Fig. 5 is a perspective view showing the hanging bar levers and associated mechanism for controlling automatic operation of the machine.

Fig. 6 is an elevation, as observed from the left side of the machine, showing the machine control keys and associated mechanism.

Fig. 7 is a fragmentary detail of a part of the releasing mechanism for the control keys shown in Fig. 6.

GENERAL DESCRIPTION

The instant invention is shown applied to the Ellis type of accounting machine, the basic principles of operation of which are so well known in the art that it is believed unnecessary to go into a detailed description thereof. Therefore only the mechanism pertinent to the instant invention will be described in detail in this specification. However, for a detailed description of the entire machine, reference may be had to the following United States patents: Nos. 55 40 and 41 (Figs. 1, 2, and 5), said main frames

1,197,276 and 1,197,278, issued September 5, 1916, to Halcolm Ellis; No. 1,203,863, issued November 7, 1916, to Halcolm Ellis; Nos. 1,939,804; 2,038,717; and 2,082,098, issued respectively December 19, 1933; April 28, 1936; and June 1, 1937, to Raymond A. Christian; and No. 2,079,355, issued May 4, 1937, to Charles L. Lee.

While the present invention is shown embodied in the well-known Ellis type of accounting machine, it is not the intention to limit this invention to this particular machine, as it may easily be adapted for use in almost any type of accounting machine.

The present machine has a plurality of denominational rows of amount keys, which in adding operations control the positioning of corresponding actuators, said actuators in turn positioning corresponding printing sectors and actuating the wheels of the selected totalizers to add therein the amount set up on the keyboard. The present machine is equipped with three adding totalizers and a consecutive number counting device. The totalizer usually referred to, in the machines of the above-mentioned patents, as the "No. 3 totalizer" is used for consecutive number counting, and its construction is modified to obtain this result.

The machine is provided with a traveling carriage which is arranged to be tabulated manually or automatically from column to column under control of tabulating stop lugs on control blocks adjustably mounted on said traveling carriage, in cooperation with tabulating stop bars and controlling means therefor.

The different totalizers are selected and conditioned for addition by means of camming lugs on the control blocks, in cooperation with hanging bar levers for the respective totalizers.

In the machine illustrated herein, the three adding totalizers and the consecutive number totalizer are selected and conditioned for sub-total operations by means of their respective sub-total control keys, and these totalizers are selected and conditioned for total operations by means of a total control key used in conjunction with their respective sub-total control keys.

The mechanism described in general above, which is pertinent to the present invention, will now be described in detail.

50 DETAILED DESCRIPTION

Framework

The mechanism of the machine embodying the instant invention is supported by main frames 55 40 and 41 (Figs. 1, 2, and 5), said main frames

connected by cross frames 42 and 43 and by various other cross frames, rods, and shafts.

In figures such as Fig. 5, where the framework is shown in phantom by dot and dash lines, where the dot and dash lines of such framework do not show behind the other parts, it indicates that such parts are in front of the framework.

The frames 40 and 41 are secured to a machine base 44, to which is secured also a case or cabinet 45 which encloses the mechanism of the machine, and which supports a laterally shiftable traveling carriage 46 later to be described.

Operating mechanism

The machine embodying the instant invention is driven by a conventional type of continuously running motor 39 (Fig. 2) supported by a framework 47, secured to the machine base 44. The armature shaft 48 of the motor 39 carries a worm wheel 49 which meshes with, and drives, a clutch driving member 50 free on a stud 51 in the framework 47. Also free on the stud 51, and contained within a boring in the driving member 50, is a clutch driven member 52 carrying a stud 53 upon which is pivoted the lower end of a link 54, the upper end of which is free on a stud 55 in a drive arm 56, secured to a main drive shaft 57 journaled in the frames 40 and 41.

A machine starting bar 58 has stems 59 and 60, parallel portions of which extend through and are guided by slots in a plate 61 mounted on the frame 40. The stem 59 is pivotally connected to a plate 62 free on a stud 63 in the frame 40. The plate 62 carries a stud 64 embraced by a bifurcated portion of one arm of a three-armed lever 65, free on a stud 66 in the frame 40, while the stem 60 is pivotally connected to an arm 67 of said lever 65. An arm of the lever 65 carries a stud 68 which cooperates with a shoulder on an arm 69 free on a stud 70 in the frame 40, and having pivotally connected thereto one end of a pitman 71, the other end of which is bifurcated to straddle a stud 72 in the frame 40. The pitman 71 carries a stud 73 embraced by a slot in an upward extension of a lever 74 free on a stud 75 in the motor framework 47.

Depressing the starting bar 58 rocks the plate 62 and the lever 65 counter-clockwise and clockwise, respectively (Fig. 2), to move the stud 68 out of engagement with the shoulder on the arm 69. This frees the arm 69, pitman 71, and lever 74 to the action of a torsion spring 76, which immediately rocks said lever 74 counter-clockwise to move a bent-over ear 77 thereof out of the path of the upper end of a clutch engaging lever 78, free on a stud 79 in the clutch driven member 52. The lever 78 has adjustably connected thereto a plate 80 carrying a stud 81, to which is anchored one end of a clutch band 82, the other end of said band being secured to the clutch driven member 52.

Moving the ear 77 out of the path of the upper end of the lever 78 frees said lever to the action of a spring 83, which immediately rocks said lever 78 counter-clockwise to expand the clutch band 82 to cause said band to grip the inner surface of the continuously rotating clutch driving member 50, whereupon said driving member immediately rotates said driven member counter-clockwise in unison therewith. One rotation of the clutch driven member 52 (Fig. 2), by means of the link 54, oscillates the arm 56 and the main drive shaft 57, first counter-clockwise

and back to normal position through an approximate angle of 60 degrees.

During return movement of the link 54 and the arm 56, a flat surface 84 on a stud carried by said link engages an upward extension 85 of the lever 74 and rocks said lever and the arm 69 clockwise to move the ear 77 into the path of the lever 78 and to move the shoulder on said arm 69 beyond the stud 68. This permits a spring 86 to rock the plate 62 clockwise and the lever 65 counter-clockwise, to return the stud 68 into the path of said shoulder, to retain the ear 77 in the path of the upper end of the lever 78 when the stud 84 passes beyond the extension 85.

Continued rotation of the clutch driven member 52 causes the upper end of the lever 78 to engage the ear 77 to contract the clutch band 82 to disengage the clutch driven member from the clutch driving member to terminate machine operation.

The lever 78 is assisted in disengaging the clutch band 82 by a cam lever 87 free on a stud 88 in the motor framework 47. The lever 87 is urged clockwise by a compressible spring 89 to maintain a camming surface 95 thereon in the path of a roller 96 mounted on an arm 97 secured to the clutch driven member 52. Near the end of rotation of the clutch driven member 52, the roller 96 engages the camming surface 95 to rock the lever 87 counter-clockwise to compress the spring 89, whereupon the declining portion of said camming surface, in cooperation with said roller, urges the clutch driven member 52 clockwise to assist the lever 78 in contracting the clutch band 82 and retaining said band contracted.

Counter-clockwise engaging movement of the arm 69 and the lever 74 is limited by a downward projection 98 of the pitman 71 contacting the stud 70. One rotation of the clutch driven member 52 and one complete oscillation of the arm 56 and main shaft 57 drive the machine mechanism through one cycle of movement, which is the requisite for adding, total, and subtotal operations.

The usual non-repeat mechanism is provided for preventing repeat cycling of the machine when the starting bar 58 is inadvertently retained depressed at the end of a machine operation.

Depressing the starting bar 58 (Fig. 2) also renders mechanism effective which causes the traveling carriage 46 to be automatically tabulated from one columnar position to the next.

In addition to the regular starting bar 58, the machine also has a vertical feed starting bar 99 and an auxiliary starting bar 100. Depressing the bar 99 releases the machine for operation, causes the traveling carriage platen roll to be automatically rotated to line-space the record material supported thereby, and prevents automatic tabulation of the traveling carriage. Depressing the auxiliary starting bar 100 initiates what is termed an idle operation of the machine, in which the automatic rotation or line-spacing of the platen and the automatic tabulation of the traveling carriage are rendered inoperative.

Amount keys

Inasmuch as the different rows of amount keys and the mechanism associated therewith are substantially duplicated in each denominational order, it is believed that a description of the one row of amount keys shown in Fig. 1, and the mechanism associated therewith, will be sufficient for the purpose of this specification.

The row of amount keys 101, shown in Fig. 1, are assembled in a keyboard framework comprising a top plate 102, a partition plate 103 for each row of keys, and right and left side plates (not shown), said side plates being secured to the frames 40 and 41. The upper ends of the keys 101 protrude through, and are guided by, corresponding openings in the top plate 102, while the lower ends of said keys are guided by square studs 105 therein, in cooperation with vertical slots 106 in the partition plate 103 for this particular bank. Each of the keys 101 has encircling the stem thereof a spring 104 compressed between a washer 107, integral with said key stems, and the bottom of an opening 108 in the plate 103. The springs 104 urge the keys 101 upwardly to compress felt washers 109 between the washers 107 and the top surfaces of the openings 108, said top surfaces being formed out of bent-over portions of said openings 108 and having slots 106 therein which admit the stems of the keys 101. The felt washers 109 deaden the sound when the amount keys are released by preventing a metal-to-metal contact between the washers 107 and the top of the openings 108.

Each row of amount keys has a detent plate 112 (Fig. 5) hinged on a rod, not shown, supported by the keyboard framework, said plates being spring-urged counter-clockwise.

Depressing one of the keys 101 causes a bent-over lip 110 on the lower end of the stem thereof to by-pass an angular lower edge 111 of the detent plate 112, whereupon said detent latches the key in depressed position. If another key is depressed in the same row, the bent-over lip 110 of said key rocks the plate 112 clockwise sufficiently to release the key previously depressed, thereby constituting what is termed "flexible key action."

Mechanism not described herein, but fully disclosed in said parent application, is provided for automatically rocking the detent plates 112 clockwise near the end of adding operations, to release the depressed amount keys.

Depressing any one of the keys 101 (Fig. 1), except the 9 key, moves the square stud 105 therein into the path of a corresponding one of a series of graduated steps 132 on an actuator rack 133, for this particular amount bank, a notched portion of the forward end of which fits in a corresponding slot in a rod 134, supported by the frames 40 and 41, and the rearward end of which is bifurcated to fit a corresponding slotted portion of a bar 135 also supported by the frames 40 and 41. It is, therefore, evident that the actuator 133 is mounted for horizontal reciprocating movement, which is imparted thereto in a manner presently to be described.

Depressing any one of the amount keys 101 also moves a zero latch (not shown), which retains the actuator 133 in zero position when no amount key is depressed, to ineffective position. There is no corresponding step 132 on the actuator 133 for the stud 105 in the 9 key, and depression of this key merely releases the zero latch and the rack travels full distance rearwardly until a wall 136, formed by the notched forward end thereof, contacts the rod 134.

The actuator 133 has a vertical slot 137 which straddles a stud 138 in a segmental portion 139 of a reducer arm 145, free on a shaft 146 journaled in the frames 40 and 41. A spring 147, tensioned between the segment 139 and a leading bar 148 extending between two similar arms 149, only one here shown, secured on the shaft 146, 75

normally maintains a projecting portion of the segment 139 in yieldable contact with the leading bar 148.

When the arm 56 (Fig. 2) is oscillated in the manner explained earlier herein, a roller 150 carried thereby, in cooperation with an irregular camming slot 151 in a cam plate 152, secured on the right-hand end of the shaft 146, rocks said shaft, the arms 149 (Fig. 1), and the leading bar 148 first rearwardly or counterclockwise and then back to normal position through an invariable excursion during each machine operation. Initial movement rearwardly, or counterclockwise, of the leading bar 148, by means of the spring 147 (Fig. 1), causes the segment 139, the reducer arm 145, and the actuator 133 to travel in unison therewith until such movement of said actuator is terminated by one of the steps 132 thereon contacting the stud 105 in the depressed amount key 101. This positions the actuator and the reducer arm 145 commensurate with the depressed amount key, and the leading bar 148 completes its rearward movement independently of the segment 139, flexing the spring 147.

Initial movement counter-clockwise of the reducer arm 145, by means of a link 152 (Fig. 1) connected between an arm 153 of said reducer arm and a printing sector 154 for this particular amount bank, positions said printing sector in proportion to the depressed amount key. The printing sector 154 is pivotally mounted on an arm 155 free on a printer shaft 156 journaled in the printer framework and the frame 40.

Referring to Fig. 2, the drive arm 56 for the main shaft 57 is connected by a link 169 to an arm 170 pivotally connected to an arm 171 integral with a hub 172 secured on the printer shaft 156. Two springs 173, stretched between the arms 170 and 171, urge said arm 170 into contact with the hub 172 and form a yieldable connection between said arms 170 and 171. Initial movement counter-clockwise of the arm 56, by means of the link 169 and arms 170 and 171, rocks the shaft 156 and a bail 159 (Fig. 1) clockwise to release the printing mechanism in the well-known manner, and as described in the above patents and in the parent application.

Directing attention to Fig. 1, after the leading bar 149 has completed its initial movement rearwardly to cause the actuator 133, arm 145, and printing sector 154 to be positioned, a roller 178 (Fig. 2) mounted on the same axle as the roller 150, said axle being supported by the arm 56, in cooperation with a camming groove 179 in an arm 180 flexibly connected to an aliner shaft 181 journaled in the frames 40 and 41, rocks said shaft clockwise, near the end of the initial movement counter-clockwise of the arm 56. Secured on the shaft 181 (Fig. 1), and moving in unison therewith, are two arms 182, only one here shown, supporting a cross bar 183 having secured thereto an alining bar 184, which, upon clockwise movement of said shaft 181, engages the proper one of a series of teeth 185 cut in the periphery of the segment 139 to aline said segment, the printing sector 154, and the actuator 133 while printing is being effected and while the totalizers are being engaged with said actuator in adding operations.

After printing has been effected, return movement clockwise of the arm 56 (Fig. 2) causes the roller 178, in cooperation with the cam groove 179, to rock the shaft 181 counter-clockwise to normal position to disengage the aliner 184 (Fig.

1) from the segment 139. Continued return movement clockwise of the arm 56 causes the roller 150, in cooperation with the cam slot 151, to return the shaft 146 and the leading bar 143 clockwise. During its return movement the leading bar 143 picks up the reducer arm 145 and returns said arm, the printing sector 154, and the actuator 133 forwardly to normal or zero position, as shown in Fig. 1, where the zero latch again becomes effective to retain said actuator and connected parts in zero position.

Totalizers

The machine embodying the present invention has four totalizers, numbered 1 to 4, respectively (Fig. 1), assembled in vertical pairs at the rear of the machine. The #1 and #2 totalizers are mounted in a framework 186, secured to the main frames 40 and 41, and two plates 187, only one here shown, connect the framework 187 to a framework 188, which supports the #3 and #4 totalizers. Each of the four totalizers has a single set of wheels, adapted to be actuated by their corresponding actuators 133.

In the invention illustrated herein, the #3 totalizer is never engaged with the actuators during adding operations, this totalizer being used as a consecutive numbering device, and is advanced step by step in a manner later to be described.

Wheels 189 and 195 of the #1 and #2 totalizers, corresponding to the denomination illustrated in Fig. 1, are arranged to cooperate respectively with rack teeth on the upper and lower surfaces of the bifurcated portion of the actuator 133. Wheels 196 and 197 of the #3 and #4 totalizers are adapted to cooperate respectively with teeth on the upper and lower surfaces of the bifurcated portion of an extension 198 connected to the actuator 133 and supported by a slotted bar 199 mounted in the framework 188.

The #1, #2, and #4 totalizers are adding totalizers, and, taking the #1 totalizer as an example, after the leading bar 148 (Fig. 1) has completed its initial movement rearwardly and the actuator 133 has been positioned by the depressed amount key 101, mechanism, controlled by the traveling carriage and presently to be described, causes the wheel 189 to be engaged with the actuator 133, and return movement forwardly of said actuator, under the influence of the leading bar 148, rotates said wheel 189 in a clockwise direction to add therein the value of the amount set up on the depressed amount key 101.

In total and sub-total operations the wheel 189 of the #1 totalizer is rocked into engagement with the actuator 133 prior to the initial movement rearwardly of said actuator, which movement reversely rotates said wheel to zero position, which position is determined by one of the diametrically opposed teeth on the tripping cam 200 coming into contact with the pawl 201. This positions the wheel 189, the actuator 133, and the printing sector 154 in accordance with the amount standing on said wheel, after which functioning of the printing mechanism causes this amount to be recorded on the record material.

In total operations the wheel 189 is rocked out of engagement with the actuator 133 prior to its return movement forwardly, and consequently said wheel remains in a zeroed condition. In sub-total operations the wheel 189 remains in engagement with the actuator 133 during its return

movement forwardly, and consequently is returned to its original position.

The totalizer engaging mechanism will be explained more in detail later in connection with the traveling carriage mechanism.

Traveling carriage

The traveling carriage 46 (Fig. 1) is supported for horizontal shifting movement on the case 45 by means of corresponding ways 202 and 203 mounted respectively near the rear of the traveling carriage and the case, said ways having therebetween ball bearings 204, which reduce friction and insure accurate alinement of the platen 177 with the printing mechanism. The front of the traveling carriage is shiftably supported by means of rollers 205, carried thereby, in cooperation with a rail 206, mounted on the case 45. A series of rollers 207 on the carriage, in cooperation with a recessed or horizontally grooved portion of the rail 206, prevents the front of the traveling carriage from tilting upwardly, and a series of brackets 208 secured to the frame of the traveling carriage, in cooperation with a flanged portion of the way 203, prevents the rear of the traveling carriage from tilting upwardly.

Accounting machine tabulating mechanism

30 Tabulating mechanism which is usually referred to as "the accounting machine tabulating mechanism" is provided for tabulating the traveling carriage to various columnar positions. Initiating machine operation by depressing the starting bar 58 (Fig. 2) causes the accounting machine tabulating mechanism to function automatically, or said tabulating mechanism may be operated manually by depressing a tabulating key 275, located on the right-hand side of the accounting machine keyboard between the vertical feed and auxiliary starting bars 99 and 100. A manipulative lever 276 (Fig. 2), one end of which protrudes through a slot in the keyboard plate 61, is provided for rendering the automatic tabulating mechanism effective or ineffective at will.

Adding operations

The Nos. 1, 2, and 4 totalizers are selected for addition by means of add hanging bar levers in cooperation with corresponding tappet lugs on a series of control blocks located in the various columnar positions of the traveling carriage on the stop bar 274 (Fig. 5). Inasmuch as similar mechanism is used to select the three totalizers for addition, it is believed that a description of the mechanism used in connection with the No. 1 totalizer will be sufficient.

A control block 305 (Fig. 5) has a tappet lug 325 adapted to cooperate with the upturned end 326 of a No. 1 add hanging bar lever 327, free on a stud 328 in the frame 42. A link 329 (Fig. 6) connects the hanging bar lever 327 to an add-control pawl 330 free on a stud 331 in the frame 41, and the rearward end of said pawl is normally in the path of a shoulder 332 on an add control plate 333, free on a stud 334 in the frame 41, and urged counter-clockwise by a spring 335. The plate 333 has a stud 336 embraced by the bifurcated upper end of a link 337, the lower end of which is pivotally connected to a lever 338 loose on a stud 339 in the frame 41. The lever 338 has secured to the lower end thereof a shoe 345, the sole of which cooperates with an arcuate surface 346 on a totalizer engaging plate 347 secured on the main shaft 57.

A stud 348 in the plate 347 rotatably supports a totalizer engaging lever 349, having in the upper end thereof a stud 350, which pivotally supports one end of a link 351, the other end of which is pivotally connected to an arm 352 secured on a No. 1 totalizer engaging shaft 353 journaled in the totalizer framework 186 (Fig. 1). Also secured on the engaging shaft 353 are two similar cams 354, only one here shown, having similar camming slots 355, which cooperate with rollers 356 mounted on opposite ends of a rockable frame 357, which supports the No. 1 totalizer. Pivotally mounted on the stud 350 (Fig. 6) is a totalizer engaging pawl 358 urged counter-clockwise by a spring 359 to normally maintain a projection thereof in contact with a stud 360 in the lever 349.

An extension 361 of the pawl 358, in cooperation with a square stud 362 in the plate 347, is adapted to rock the No. 1 totalizer into engagement with the actuators 133 in adding operations, and a square stud 363, in the plate 347, in cooperation with a prominence on the lever 349, is adapted to disengage the No. 1 totalizer from the actuators 133 near the end of adding operations.

Upon operation of the machine, initial movement clockwise of the main shaft 51 and the totalizer engaging plate 247, as viewed in Fig. 6, moves the arcuate surface 346 out of the path of the shoe 345 to release the lever 338, link 337, and plate 333 to the action of the spring 335. However, when the traveling carriage is so positioned that the tappet 325 (Fig. 5) does not engage the upward extension 326 of the No. 1 hanging bar lever 327, the pawl 330 remains in the path of the shoulder 332 of the plate 333, as shown in Fig. 6, to obstruct counter-clockwise movement of said plate, under influence of the spring 335. When the above condition prevails, initial movement clockwise of the plate 347 causes an upward extension 364 of the pawl 358 to engage the stud 336 to rock the extension 361 out of the path of the stud 362, thereby permitting the lever 349 to continue to pivot relatively to the plate 347, and consequently the No. 1 totalizer engaging mechanism does not function.

When the traveling carriage 46 is tabulated to the columnar position corresponding to the control block 305 (Fig. 5), the stop lug 304 on said block, contacting the tabulating bars controlled by the tabulating mechanism, arrests the traveling carriage in a position wherein the tappet lug 325 engages the upward extension 326 of the lever 327, thus rocking said lever clockwise, as viewed in Fig. 5. Said clockwise movement of the lever 327 raises the link 329 (Fig. 6) to rock the pawl 330 counter-clockwise out of the path of the shoulder 332. In this instance, when the arcuate surface 346 moves out of the path of the shoe 345, upon initial movement clockwise of the plate 347, the spring 335 rocks the plate 333, link 337, and lever 338 counter-clockwise to move the stud 336 out of the path of the extension 364.

Therefore, after the actuators 133 have been positioned by the depressed amount keys, and near the end of the initial movement clockwise of the plate 347, the extension 361 of the pawl 358 engages the stud 362. This terminates movement of the lever 349 in relation to the plate 347 and causes said lever to move in unison with said plate, which movement, by means of the link 351, rocks the arm 352, shaft 353, and cams 354 counter-clockwise. Counter-clockwise movement

of the cams 354, by means of the slots 355 therein, in cooperation with the rollers 356, rocks the totalizer frame 357 clockwise to engage the wheels 189 of the No. 1 totalizer with the actuators 133. The No. 1 totalizer remains in engagement with the actuators 133 during their return movement forwardly, to add in said totalizer the amount set up on the keyboard.

After the actuators 133 have completed their return movement, and near the end of the return movement counter-clockwise of the plate 347, the stud 363 engages the lever 349, causing said lever to move counter-clockwise in unison with said plate 347, to rock the arm 352, shaft 353, and cams 354 clockwise to normal positions, as here shown, to disengage the wheels 189 of the No. 1 totalizer from the actuators 133. Return movement counter-clockwise of the plate 347 (Fig. 6) causes the arcuate surface 346, in cooperation with the sole of the shoe 345, to rock the lever 338, link 337, and plate 333 clockwise to normal positions, as here shown, to move the shoulder 332 on said plate beyond the end of the pawl 330 so that said pawl may again move into the path of said shoulder to obstruct counter-clockwise movement of the plate 333.

A train of mechanism similar to that described for engaging the No. 1 totalizer with the actuators is provided for each one of the four totalizers. For a detailed description of such totalizer engaging mechanisms, reference may be had to the Christian Patent No. 2,038,717.

The Nos. 1, 2, 3, and 4 totalizers are selected and conditioned for sub-total operations by means of their respective sub-total keys 372 to 375 inclusive (Figs. 5 and 6), and a total operation may be performed in any one of the four totalizers by using a total key 376 in conjunction with the proper one of the sub-total keys 372 to 375 inclusive. It is believed that a description of a sub-total and a total operation in connection with the No. 1 totalizer will be sufficient, as the mechanism and the manner in which it functions are substantially the same for each of the totalizers.

A repeat key 371, the sub-total keys 372 to 375 inclusive, and the total key 376 are mounted on the left side of the accounting machine keyboard. The lower ends of said keys extend through corresponding slots in the angle plate 127 and the upper ends of said keys extend through corresponding slots in the keyboard plate 126. Each of said keys has a spring, similar to the spring 128 for the release key 125, which urges said keys upwardly to normally maintain a shoulder, formed on the upper end thereof, in contact with the lower surface of the plate 126.

Depressing the No. 1 sub-total key 372 (Fig. 6) moves a notch 377 therein opposite a bent-over ear 378 on a key latch lever 379 pivoted on a stud 380 in the frame 41, whereupon a spring 381 urges said lever clockwise to latch said key 372 depressed. Clockwise movement of the lever 379 causes a stud 382 in the lower end thereof, in cooperation with a camming surface 383 on a lever 384 free on a stud 385 in the frame 41, to rock said lever clockwise. Upon clockwise movement of the lever 384, an extension thereof, in cooperation with a stud 386 in a lever 387, also free on the stud 385, rocks said lever 387 clockwise in unison therewith. A spring 388 yieldingly connects the lever 387 to a totalizer engaging pawl 389, also free on the stud 385 and mounted adjacent said lever 387, said spring 388 normally maintaining said pawl in contact with a stud 390

in the lever 387. Also pivotally mounted on the lever 387 is a totalizer disengaging pawl 391, urged counter-clockwise by a spring 392 into engagement with a stop on said lever 387. Clockwise movement of the lever 387 moves the ends of the pawls 389 and 391 into the path of the lower end of the engaging lever 349, said lower end being reinforced by a block 393.

Upon operation of the machine, initial movement clockwise of the plate 347 (Fig. 6) causes the end of the lever 349 to engage the pawl 389 to rock the wheels 189 of the No. 1 totalizer into engagement with the actuators 133 in the manner explained hereinbefore. Initial movement rearwardly of the actuators 133 reversely rotates the wheels 189 to zero, to position said actuators and the printing sectors to the amount standing on said totalizer wheels. When the plate 347 nears the end of its initial movement, and after printing has been effected, mechanism presently to be described rocks the latch 379 counter-clockwise to disengage the ear 378 thereof from the notch 377 to release the No. 1 sub-total key 372. This counter-clockwise restoring movement of the latch 379 permits the levers 384 and 387 to be returned, by gravity, counter-clockwise to normal positions to move the pawls 389 and 391 out of the path of the lower end 393 of the lever 349, so that the pawl 391 will not engage the lever 349 and disengage the wheels 189 from the actuators 133. As the wheels 189 remain in engagement with the actuators 133 during their return movement forwardly, said wheels are returned to their original positions to reenter the amount in the No. 1 totalizer, after which the stud 363, near the end of return movement of the plate 347, engages the lever 349 to disengage the wheels 189 from the actuators.

Depressing the total key 376 in conjunction with the No. 1 sub-total key 372 selects and conditions the No. 1 totalizer for a total operation, which is exactly like a sub-total operation, with the exception that the latch 379 is not rocked counter-clockwise to release the sub-total key 372 near the end of the initial movement of the plate 347. Consequently the pawl 391 remains in the path of the projection 393 and said projection by-passes said pawls during initial movement clockwise of the plate 347. Return movement counter-clockwise of the plate 347 causes the end of the lever 349 to engage the pawl 391 to rock the totalizer wheels 189 out of engagement with the actuators 133 prior to return movement forwardly of said actuators 133, thereby leaving the wheels 189 of the No. 1 totalizer in a zeroized condition. Near the end of machine operation the latch 379 is rocked counter-clockwise, in a manner presently to be described, to release the No. 1 sub-total key 372.

Release of control keys

Inasmuch as the time of release of the sub-total keys 372 to 375 inclusive determines whether the operation is a sub-total or a total operation, it is impossible to use the regular amount key releasing means for releasing these keys, and therefore a separate releasing mechanism has been provided for this purpose.

When the No. 1 sub-total key 372 (Fig. 6) is depressed, clockwise movement of the latch 379, under influence of the spring 381, causes the ear 378, in engagement with a projection 399 of a key release bar 400, to shift said bar forwardly. The bar 400 is shiftably mounted by means of a slot in the forward end thereof, in cooperation

with a stud 401 in a foot-shaped lever 402 pivoted on a stud 403 in the frame 41, and by means of a slot 404 in the rearward end thereof, in cooperation with a stud 405 in the upper end of a lever 406 fulcrumed on a stud 407 in the frame 41. Mounted adjacent the bar 400, and somewhat similar in outline thereto, is an auxiliary release bar 408 (Figs. 6 and 8), the forward end of which is slotted to straddle an extension of the stud 401, and the rearward end of which is pivoted on an extension of the stud 405.

In sub-total operations the total key 376 is not depressed, which causes the enlarged portion of a wedge 409, pivotally mounted on the stem of said key, to be positioned between studs 410 and 411 carried respectively by the bars 400 and 408, to connect said bars so that they will shift forwardly in unison when the No. 1 sub-total key is depressed. Forward shifting movement of the bar 408 rocks the lever 406 clockwise to move a foot-shaped portion 412 thereof into position to be engaged by an extension 413 of the stud 348 in the plate 347. Initial movement clockwise of the plate 347 engages the No. 1 totalizer wheels with the actuators 133, as explained above. Near the end of initial movement clockwise of the plate 347, and after printing has been effected, the extension 413 engages the foot 412 to rock the lever 406 counter-clockwise to shift the bars 408 and 400 rearwardly to rock the latch 379 counter-clockwise to disengage the ear 378 thereof from the notch 377 to permit the key 372 to be spring-returned upwardly to undepressed position.

Return movement counter-clockwise of the latch 379 (Fig. 6) permits the lever 384 and the pawls 389 and 391 to rock counter-clockwise about their pivot 385 to move said pawl 391 out of the path of the lever 349. This permits the wheels 189 of the No. 1 totalizer to remain in engagement with the actuators 133 during their return movement forwardly, to return said wheels to their original positions, to reenter therein the amount of the sub-total. At the beginning of return movement counter-clockwise of the plate 347, the extension 413 is withdrawn from the foot 412 and the spring 381 returns the latch 379 and connected parts clockwise until the ear 378 comes to rest on the edge of the stem of the key 372, as shown in Fig. 6. Near the end of return movement counter-clockwise of the plate 347, the stud 363 engages the lever 349 and disengages the No. 1 totalizer wheels 189 from the actuators 133.

If it is desired to perform a total operation in the No. 1 totalizer, the total key 376 is depressed in conjunction with the No. 1 sub-total key 372. Depressing the total key 376 (Fig. 6) moves a notch 414 therein opposite a bent-over ear 415 of a latch 416, pivoted on a stud 417 in the frame 41, whereupon a spring 418 urges said latch 416 clockwise to engage the ear 415 with the notch to retain the total key depressed. Depressing the total key 376 carries the wedge 409 (see also Fig. 7) downwardly in unison therewith to move the enlarged portion thereof from between the studs 410 and 411, to disconnect the bar 400 from the bar 408. An upwardly extending finger of the wedge 409, in cooperation with the studs 410 and 411, retains said wedge in proper relationship with said studs.

It is, therefore, evident that when the extension 413 of the stud 348 (Fig. 6) strikes the lever 406 and shifts the bar 408 rearwardly, during the

initial movement of the plate 347, no movement will be imparted to the bar 400; consequently the latch 379 will remain in its clockwise position to retain the No. 1 sub-total key 372 depressed and to retain the pawls 389 and 391 in the path of the lever 349.

Initial movement clockwise of the plate 347 (Fig. 6) causes a stud 418 carried thereby to by-pass the lower end of a lever 419, pivotally mounted on the bar 400, said lever being yieldingly retained in a neutral position by a spring 420. At the beginning of the return movement counter-clockwise of the plate 347, the lower end 393 of the lever 349 engages the pawl 391 to rock the No. 1 totalizer wheels 189 out of engagement with the actuators 133, before said actuators start their return movement forwardly, thereby leaving said wheels in a zeroed condition. Continued counter-clockwise movement of the plate 347 causes the stud 418 to engage the lower end of the lever 419 to rock said lever clockwise until a surface 421, on the upper end thereof, contacts a stud 422 in the frame 41, whereupon continued clockwise movement of said lever shifts the bar 400 rearwardly. Rearward movement of the bar 400 causes the projection 399 thereon to rock the latch 379 counter-clockwise to disengage the ear 378 from the notch 377 in the key 372 to permit said key to be spring-returned upwardly to undepressed position and to permit the pawls 389 and 391 to be returned counter-clockwise out of the path of the lever 349 to normal position, as shown in Fig. 6. When the stud 418 moves beyond the lower end of the lever 419, the spring 381 returns the latch 379 clockwise until the ear 378 comes to rest on the edge of the key 372.

The total key 376 (Fig. 6) is released just after the No. 1 sub-total key 372 in the following manner.

Initial movement clockwise of the main shaft 57, the plate 347, and a disc 122, causes a stud 121 in said disc to by-pass the angular nose of a spring-pulled tappet 423, free on a stud 424 in the frame 41. Return movement counter-clockwise of the disc 122 causes the stud 121 to rock the tappet 423 clockwise, whereupon a stud 425, carried by said tappet, in cooperation with an angular surface 426 on an arm 427 integral with the latch 416, rocks said latch counter-clockwise to disengage the ear 415 from the notch 414 to permit the total key 376 to be spring-returned upwardly to undepressed position, as here shown. After the stud 121 moves beyond the tappet 423, the spring 418 returns the latch 416 and the arm 427 clockwise until the ear 415 comes to rest on the edge of said key 376.

It should be remembered that in both total and sub-total operations, the pawl 389 (Fig. 6), in cooperation with the lower end of the lever 349, engages the wheels 189 of the No. 1 totalizer with the actuators 133 prior to the initial movement rearwardly of said actuators. Likewise it should be remembered that the sub-total keys 373, 374, and 375 have mechanism similar to, and functioning in substantially the same manner as, the sub-total key 372 to control their respective totalizers Nos. 2, 3, and 4.

Consecutive number mechanism

As previously explained, the No. 3 totalizer (Figs. 1 and 3) is reserved for the accumulation of a consecutive number which is printed on the various detachable portions of the record slips. In the present arrangement, mechanism, func-

tioning when the No. 4 totalizer is selected for an adding operation, causes the units wheel of the consecutive number accumulator to be advanced one digit. In the system disclosed in the parent application, the No. 4 totalizer is selected for addition only once during a series of operations required to complete a record slip. It is therefore evident that the consecutive number accumulator will be advanced only one digit during each series of operations. Other operations performed in the No. 4 totalizer—for example, sub-total and total operations—have no effect upon the advancing mechanism for the consecutive number accumulator.

The No. 3 totalizer shaft (Fig. 4), which supports the consecutive number wheels 196, is mounted in a rockable frame 632, similar to and functioning in exactly the same manner as the frame 357 (Fig. 6) for the No. 1 totalizer, explained earlier herein. The frame 632 is pivoted on trunnions supported by the frame 188 (Fig. 3) and the extreme right and left arms of said frame 632 each support a roller 633 (only one here shown) which engage their respective cam slots 634 in two engaging cams 635 secured on an engaging shaft 636 journaled in the framework 188. A flying lever mechanism and its totalizer engaging pawl, similar to that illustrated in Fig. 6 for the No. 1 totalizer and explained earlier herein, controls the engaging shaft 636 for the consecutive number accumulator to engage and disengage the wheels 196 (Figs. 1 and 4) with and from the extensions 198 of the actuators 133 in total or sub-total timing.

The consecutive number accumulator is not provided with an add hanging bar lever and associated mechanism for selecting and conditioning said accumulator for adding operations, but instead is provided with a step-by-step advancing mechanism now to be described.

A trip pawl 637 (Fig. 4), for the units consecutive number wheels 196, is pivoted on a rod 638 supported by the framework 632, and said trip pawl is urged counter-clockwise by a spring 639 to normally engage a rod 645 supported by the frame 632. A bent-over ear 646 of the pawl 637 normally engages a shoulder 647, on a cam lever 648 pivoted on a rod 649 supported by the frame 632, to normally restrain said lever 648 against the action of a spring 650, which is tensioned to urge said lever counter-clockwise. The lever 648 has a cam slot 651 into which extends a stud 652 in a segment 653 pivoted at 654 to a plate 644 supported by the framework 188 (Fig. 3). Gear teeth in the segment 653 (Fig. 4) mesh with the teeth of the units consecutive number wheel 196 when the consecutive number accumulator is out of engagement with the actuator extension 198, as here shown.

The pawl 637 has a shoulder 655 which cooperates with a finger 656 integral with a shaft 657 journaled in the framework 188. Secured on the right-hand end of the shaft 657 (Fig. 3) is an arm 658, said arm and said shaft urged clockwise by a spring 659 to normally maintain a shoulder on said arm in contact with a stop stud 660 in the frame 188. The arm 658 carries a stud 661 which cooperates with the upper end of a pawl 662 pivotally mounted on the upper end of a pitman 663, the lower end of which is pivoted to a crank 664 on the right-hand end of a No. 4 totalizer engaging shaft 665 journaled in the framework 188. A spring 666 urges the pawl 662 clockwise into engagement with a stud 75 667 in the pitman 663.

The engaging mechanism for the No. 4 totalizer, comprising the shaft 665 and engaging cams 667 mounted thereon, having camming slots 668 which cooperate with their respective rollers 669, is similar in every respect to the No. 1 totalizer engaging mechanism illustrated in Fig. 6 and described earlier herein.

A link 670 connects the pitman 663 to the cam arm 180 for the actuator segment aliner 184, which, it will be recalled, is rocked clockwise by the roller 178 (Fig. 2) on the arm 56 near the end of the initial movement counter-clockwise of said arm and after the actuators and their associated segments have completed their initial movements rearwardly.

Clockwise movement of the arm 180, by means of the link 670, rocks the segment 663 also clockwise to move the upper end of the pawl 662, which is normally out of the path of the stud 661, beneath said stud. After the pawl 662 has been rocked beneath the stud 661, the shaft 665 is rocked counter-clockwise to engage the wheels of the No. 4 totalizer with the actuators in add time, which movement causes the crank 664 to shift the pitman 663 upwardly, whereupon the pawl 662 engages the stud 661 and rocks the arm 658 and the shaft 657 counter-clockwise, contrary to the action of the spring 659. Counter-clockwise movement of the shaft 657 (Figs. 3 and 4) and the finger 656 causes said finger, in cooperation with the shoulder 655, to rock the pawl 637 clockwise, against the action of the spring 639, to disengage the ear 646 from the shoulder 647 of the lever 643. This releases the lever 648 to the action of the spring 650, which immediately rocks said lever counter-clockwise, causing the cam slot 651, in cooperation with the stud 652, to rock the segment 653 counter-clockwise, to rotate the units wheel 196 one tooth space in a clockwise direction, to add one digit in the consecutive number accumulator. Counter-clockwise movement of the lever 643 is terminated by a projection 671 thereon contacting the shaft 657. When any one of the lower order wheels 196 passes through zero, one of two diametrically opposed projections on a tripping cam 683, integral therewith, trips a pawl similar to the pawl 637, and said pawl releases a cam lever, similar to the lever 643, which, by means of a sector similar to 653, immediately advances the next higher order wheel 196 one digit.

A restoring bar 672 (Fig. 4) is provided for restoring the tripped levers 648, sectors 653, and pawls 637 to normal positions. The bar 672 is actuated by the totalizer engaging mechanism and functions only after the wheels 196 have been disengaged from their sectors 653 and engaged with the actuator extensions 198. Inasmuch as the consecutive number accumulator is advanced by the finger 656 and is not engaged with the extensions 198 for advancing thereby, the bar 672 receives no movement at this time and therefore the levers 648, sectors 653, and pawls 637 remain in tripped positions until a sub-total or total operation is performed in the No. 3 accumulator, at which time the bar 672 is actuated.

The restoring bar 672 has integral therewith two similar arms 673, only one here shown, fulcrumed on trunnions in the frame 188, said trunnions in axial alinement with the rod 649. At the beginning of sub-total or total operations, in the consecutive number accumulator, the wheels 196 (Fig. 4) are rocked out of engage-

ment with the sectors 653 and into engagement with the actuator extensions 198. Immediately thereafter the restoring bar 672 is rocked clockwise, and, in cooperation with the projections 674 of the levers 648, restores said levers and the sectors 653 to normal positions, whereupon the springs 639 restore the pawls 637 counter-clockwise to untripped positions to cause the ears 646 to move into the path of the shoulders 647 in preparation for the next advancing movement of the consecutive number device.

In the system described in the parent application, a series of operations are necessary to complete one record slip. In the first of said 15 series of operations the consecutive number accumulator is advanced one digit, as explained above. Thereafter the consecutive number accumulator is sub-totalized several times to print the consecutive number upon the various portions 20 of the record slip. In the first of these sub-total operations the tripped levers 648, sectors 653, and pawls 637 are restored by the bar 672 to untripped positions, as explained above.

When the No. 4 totalizer is selected and conditioned for sub-total or total operations (Figs. 25 3 and 4), the engaging shaft 665 and the crank 664 are rocked counter-clockwise, at the beginning of machine operation, prior to initial movement clockwise of the arm 180. Consequently 30 the upper end of the pawl 662 moves above the bottom of the stud 661 and upon initial movement of the arm 180 and the pitman 663, said pawl 662 engages said stud 661 and is rocked thereby relatively to said pitman 663, contrary to the action of the spring 656 and obviously without imparting any movement to the arm 658 and the shaft 657. It is therefore evident that, when total and sub-total operations are performed in the No. 4 totalizer, the trip pawl 637 (Fig. 4) will not be released, and the units wheel 196 of the consecutive number accumulator will not be advanced.

After the restoring bar 672 has restored the 45 lever 648, sector 653, and pawl 637, said bar is latched in an intermediate position a slight distance away from the extension 674 and near the end of the operation the latch is disengaged and said bar 672 is spring-returned counter-clockwise to normal position, as here shown. The above action of the restoring bar 672 is necessary for transferring amounts from lower to higher denominations, during adding operations in the regular totalizers, but is unnecessary in the No. 3 totalizer, where the No. 3 totalizer has been modified for the accumulation of a consecutive 50 number and is not actuated by the actuators 198 (Fig. 1).

Summarizing briefly the foregoing description of the consecutive number mechanism, it will be seen that the No. 3 totalizer is utilized only as 60 a consecutive number accumulator, and that this accumulator is advanced one step each time the No. 4 totalizer performs an adding operation, but is not advanced when other than adding operations are performed in said No. 4 totalizer.

While the form of mechanism herein shown and described is admirably adapted to fulfil the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class described, having

means to operate the machine, a totalizer, actuators for the totalizer, and a consecutive number device, the combination of means to engage the totalizer with the actuators; means to control the engaging means to cause the totalizer to perform a certain function; means to advance the consecutive number device; means, comprising a member connected to the engaging means, to release the advancing means; and means whereby the operating means moves the member into cooperative relationship with the releasing means, when the controlling means therefor is effective, to cause the consecutive number device to be advanced.

2. In a machine of the class described, having means to operate the machine, a totalizer, actuators for the totalizer, and a consecutive number device, the combination of means to engage the totalizer with the actuators; means to control the engaging means to cause the totalizer to perform a certain function; means to align the actuators in set positions; means to advance the consecutive number device; means operated by the engaging means, when the engaging means is effective, to release the advancing means, said releasing means being normally out of cooperative relationship with said advancing means; and connections between the aligning means and the releasing means, to move said releasing means into cooperative relationship with the advancing means to cause the consecutive number device to be advanced.

3. In a machine of the class described, having means to operate the machine, a totalizer, actu-

ators for the totalizer, and a consecutive number device, the combination of means to engage the totalizer with the actuators; means to control the engaging means to cause the totalizer to perform a certain function; means to align the actuators in set positions; means to advance the consecutive number device; and means, including a member operable by the engaging means and movable by the aligning means into cooperative relationship with said advancing means, when the engaging means is effective, to cause the consecutive number device to be advanced.

4. In a machine of the class described adapted to perform item entry and total taking operations, having a totalizer, actuators for the totalizer, a consecutive number device, and means to operate the machine, the combination of means to engage the totalizer with the actuators, said engaging means operable at one time during item entry machine operations and at a different time during total taking operations; a normally ineffective means operated by said totalizer engaging means to operate said consecutive number device to advance the consecutive number device one unit when the totalizer is engaged for a certain one of said kinds of operations; and means to render the normally ineffective means effective at the same time during each machine operation so that the normally ineffective means is rendered effective before the engaging means is operated during one of said kinds of operations and after the engaging means is operated during another one of said kinds of operations.

PAUL H. WILLIAMS.

CERTIFICATE OF CORRECTION.

Patent No. 2,284,786.

June 2, 1942.

PAUL H. WILLIAMS.

It is hereby certified that error appears in the above numbered patent requiring correction as follows: In the heading to the printed specification, line 8, for the serial number "284,249" read --285,249--; and that the said Letters Patent should be read with this correction therein that the same may conform to the record of the case in the Patent Office.

Signed and sealed this 7th day of July, A. D. 1942.

(Seal)

Henry Van Arsdale,
Acting Commissioner of Patents.
